(57) **CLAIM**

The ornamental design for an assemble game, as shown and described.

DESCRIPTION

FIG. 1 is a top, left and front perspective view of the assemble game showing my new design;
FIG. 2 is a top, right and rear perspective view thereof;
FIG. 3 is a top plan view thereof;
FIG. 4 is a front elevation view thereof;
FIG. 5 is a right side elevation view thereof;
FIG. 6 is a left elevation view thereof;
FIG. 7 is a rear elevation view thereof;
FIG. 8 is a bottom plan view thereof;
FIG. 9 is a perspective view showing one of the six identical components like those on the lower side of the diagonal division in FIGS. 3, 4 and 7 and the upper side of the diagonal division in FIGS. 5, 6 and 8;
FIG. 10 is a top plan view of the component in FIG. 9;
FIG. 11 is a front elevation view of the component in FIG. 9;
FIG. 12 is a right side elevation view of the component in FIG. 9;
FIG. 13 is a left side elevation view of the component in FIG. 9;
FIG. 14 is a rear elevation view of the component in FIG. 9;
FIG. 15 is a bottom plan view of the component in FIG. 9;
FIG. 16 is a perspective view showing one of the six Identical components like those on the upper side of the diagonal division in FIGS. 3, 4 and 7 and on the lower side of the diagonal division in FIGS. 5, 6 and 8;
FIG. 17 is a top plan view of the component in FIG. 16;
FIG. 18 is a front elevation view of the component in FIG. 16;
FIG. 19 is a right side elevation view of the component in FIG. 16;
FIG. 20 is a left side elevation view of the component in FIG. 16;
FIG. 21 is a rear elevation view of the component in FIG. 16;
and,
FIG. 22 is a bottom plan view of the component in FIG. 16.
